DESIGN FOR A PLASTIC PACKAGING REINFORCING SHEET

Charles H. Luby, Philadelphia, Pa.

Application December 29, 1939, Serial No. 89,195

Term of patent 14 years

To all whom it may concern:

Be it known that I, Charles H. Luby, a citizen of the United States, residing in Philadelphia, county of Philadelphia, State of Pennsylvania, have invented a new, original, and ornamental Design for a Plastic Packaging Reinforcing Sheet, of which the following is a specification, reference being had to the accompanying drawing, which forms a part thereof.

Figure 1 is a plan view of a section of a plastic

packaging reinforcing sheet, showing my new design.

Figure 2 is an end elevation of the same.

The essential features of my design reside in the juxtaposed arrangement of the annular elements joined together as shown.

I claim:

The ornamental design for a plastic packaging reinforcing sheet, as shown and described.

CHARLES H. LUBY.
